COMBINED PORTABLE BAR AND AQUARIUM

Nathaniel V. Lampkins, Washington, D. C.

Application May 24, 1955, Serial No. 36,191

Term of patent 7 years

(Cl. D33—19)

Fig. 1.

Fig. 2.

Fig. 3.

Fig. 4.

Fig. 1 is a front elevational view of a combined portable bar and aquarium, showing my new design.

Fig. 2 is an end elevation.

Fig. 3 is a rear elevation.

Fig. 4 is a top plan view.

The broken lines in the aquarium element of the combination, representative of fish and flora, are for illustrative purposes only.

I claim:

The ornamental design for a combined portable bar and aquarium, as shown and described.
